(57) CLAIM

The ornamental design for a lace-up jeans, as shown and described.

DESCRIPTION

FIG. 1 is a front view of the lace-up jeans showing the new design;

FIG. 2 is a rear view thereof;

FIG. 3 is a right side view thereof; and,

FIG. 4 is a left side view thereof.

The broken line portions of the drawings are for illustrative purposes only and form no part of the claimed design.
